UNITED STATES PATENT OFFICE.

ANDREW SORLIEN, OF AUSTIN, MINNESOTA.

SAFETY-STOP FOR ELEVATOR-MOTORS.

1,249,537.

Specification of Letters Patent. Patented Dec. 11, 1917.

Application filed June 2, 1917. Serial No. 172,529.

To all whom it may concern:

Be it known that ANDREW SORLIEN, a subject of King Hokan 7th, Norway, residing at Austin, in the county of Mower and State 5 of Minnesota, has invented certain new and useful Improvements in Safety-Stops for Elevator-Motors, of which the following is a specification, reference being had to the accompanying drawings.

10 This invention relates to safety appliances for stopping motors or engines upon the happening of a predetermined contingency, and particularly to means for stopping the movement of elevators carrying coal, or 15 other like material, if the chute into which the elevating buckets discharge becomes clogged or overfilled.

In elevators where coal or like material is carried upward to an upper level by means 20 of elevators and there discharged into a chute, it is a common thing for the chute to become filled up or clogged, whereupon the coal discharged from the elevator buckets is liable to fall downward through 25 the open structure within which the elevator is mounted and serious accidents have occurred in this manner, particularly in those elevators where an operator stands beside the scales below the chute, the coal 30 carried over by the buckets after the chute is filled being very liable to be discharged upon the operator's head.

The general object of my invention is to 35 provide a safety device applicable to elevators of this character in which the motor operating the elevators will be stopped as soon as the discharging chute becomes filled or clogged.

A further object of the invention is to 40 provide a construction of this character in which the motor is an electric motor and in which a switch is provided for disconnecting the motor from the source of energy and in which means are provided to cause the 45 opening of the switch when the discharging chute becomes clogged.

And a further object is to provide a trap 50 board or platform upon which coal or other material is discharged, if the hopper or discharging chute becomes filled, this trap board being operatively connected to a switch actuating means to shift the switch if any coal or other matter drops upon the platform.

Other objects will appear in the course of 55 the following description.

My invention is illustrated in the accompanying drawings, wherein:

Figure 1 is a vertical sectional view 60 through an elevator with my safety device applied thereto;

Fig. 2 is a fragmentary sectional view on the line 2—2 of Fig. 1;

Fig. 3 is a fragmentary sectional view 65 on the same lines as Fig. 2, but with the endless carrier, its supporting wheels, etc., removed so as to show the trap board;

Fig. 4 is a top plan view of the hopper 70 31 showing a trap board extending thereover; and

Fig. 5 is a fragmentary vertical sectional view on the line 5—5 of Fig. 1, looking in the direction of the arrows.

In these figures I have shown an ordinary 75 form of elevator house, which is designated 10. On the floor 11, above the basement 12, there is disposed an electric motor 13 and also a band wheel 14, which is operatively connected to the electric motor and driven thereby. This electric motor is controlled 80 by the starting box or controller 15 of any usual construction and this in turn is connected to the source of electricity through the knife blade switch 16, which is also of 85 any suitable construction.

Disposed within the basement is a sprocket wheel or wheels 17 and disposed in the upper end of the house 10 is a sprocket wheel or wheels 18, which are located immediately 90 above the sprocket wheels 17. The sprocket chains forming an endless carrier 19, which may be of any suitable construction, pass around the sprocket wheel or wheels 17 and extend vertically upward over the sprocket wheels 18 and then horizontally over 95 sprocket wheels 20 and then downward and toward the first described flight of the sprocket chains and over sprocket wheels 21, and then vertically downward to the sprocket wheels 17 again. The sprocket 100 chains or endless carrier 19 carry a plurality of buckets 22 which may be of any suitable or ordinary construction. The band wheel 14 carries upon it a band 23, which extends upward and over a pulley 24, the shaft of 105 which carries a gear wheel 25. This gear wheel 25 meshes with a relatively large gear wheel 26, which in turn meshes with a pinion

27 mounted upon the shaft of the sprocket wheels 18. Thus power is transmitted to the sprocket wheels 18 and thus the endless carrier with its buckets is driven.

5 Inclosing the upper portion of the vertical flight of the endless carrier is a housing 28, which extends upward and then laterally for a distance toward the sprocket wheels 20, as at 29. This horizontal portion 29 of 10 the housing discharges into a chute 30, which chute extends downward and in turn discharges into a hopper 31. This hopper in turn discharges into a chute 32, extending to the exterior of the building and discharging into a pivoted trough or chute 33, normally held in a raised position by means of the counterweight 34, but which chute may be lowered so as to discharge into a wagon or other receptacle. The endless carrier dips into the hopper 35, which in turn receives its coal or other material from a chute 36, extending upward to the ground and above this chute 36 are disposed the railway tracks 37, whereby cars laden with 20 coal or other material may discharge their products into the chute and thus into the hopper.

30 In elevators of this character an operator usually stands beside a scale 38 and weighs the coal discharged from the chute 33. In elevators of this character, there are no floors above the first floor, but the various levels of the elevator are open or skeletal and if the chute 30 becomes clogged or if 35 the hopper 31 becomes filled up with coal or other products and the chute 30 becomes filled up, then the coal contained in the buckets 22 and passing along the horizontal portion 29 of the housing 28 cannot be discharged into the chute 30, but coal is carried along by the buckets and is discharged at a point where the buckets rotate around the sprocket wheels 20, the coal falling downward onto the operator who stands by the 40 weighing machine or onto the engineer who is attending to the motor. In order to avoid this objection, I provide a vertically disposed chute 39, just forward of the chute 30 and having its upper open end disposed on a 45 level with the bottom of the housing 29. This chute 39 discharges upon a trap board 40, as it may be termed, which is hingedly mounted upon a beam 41, or upon any other suitable support, and which is normally held 50 in a horizontal position by means of a contractile spring 42, the upper end of which may be attached to one of the beams 43 forming part of the structure.

Attached to this trap board 40 is a wire 60 or cable 44, which extends upward over a pulley 45 and then extends downward and is connected to an angularly bent lever 46, pivotally mounted in any suitable manner and having its relatively short end 47 disposed behind the handle 48 of the knife

blade slit 16. Now when any coal is discharged from one of the buckets into the chute 29, it will drop upon the trap board, cause the trap board to lower against the force of the spring, and this will draw upward on the wire cable and upon the long arm of the lever 46, causing the short arm of this lever to force the knife blade switch outward, thus breaking the circuit to the motor. This will almost immediately stop 70 the motor and stop the movement of the endless carrier. When the coal within the hopper 31 has been discharged or the coal within the chute 30 has been discharged or removed so as to dislodge the coal and relieve the clogged chute, then the lever 46 may be drawn downward which will draw the trap board up into its normal position and the switch may be again turned to close the circuit from the motor to the source of 75 energy. 80

85 In actual practice, the trap board 40 will be operated by even two pounds of coal falling upon it and will trip the switch. In actual practice I have found that when the 90 switch is tripped the endless element 19 will run about the distance between adjacent buckets before the endless element stops. It will be seen that if the chute 30 were full and there was no provision made for stopping the motor 18, then the coal or other material would lodge in the portion 29 of the housing 28 and clog this portion of the housing, thus breaking the buckets and injuring the machinery. I have found that 95 this automatic tripping device saves a very great percentage of damage to machinery and from breaking buckets. These buckets break when chute 30 becomes clogged or is filled up and under normal circumstances it 100 requires one man to watch the chute 30 to see that it is not "over-flooding" or does not become clogged. My safety mechanism does away with the necessity of this watchman. 105

110 While I have illustrated a certain embodiment of this invention which is entirely effective under the circumstances illustrated, yet it will be obvious that the mechanism may be modified in many ways to suit various conditions, without departing from the 115 spirit of the invention.

Having described my invention, what I claim is:

1. In a mechanism of the character described, an endless elevator having a vertical flight and a horizontal flight, a chute disposed beneath the horizontal flight of the elevator and upon which the elevator discharges, a chute disposed at the end of the first named chute, a motor for driving the 120 elevator, electrical connections to the motor including a switch, a pivoted trap board mounted beneath the second named chute and upon which material will be discharged from said chute, said trap board rotating 125 130

under the weight of said material, and flexible connections from said trap board to the switch causing the opening of the switch when the trap board is rotated.

- 5 2. In an elevator structure, an endless elevator having a vertical flight and a horizontal flight and including buckets, a chute disposed beneath the portion of the horizontal flight of the endless elevator and into
10 which said buckets discharge, a motor for operating the endless elevator, a device for cutting off power to the motor, a vertically disposed chute mounted just beyond the first named chute and into which said buckets
15 will discharge when the first named chute is filled or clogged, a vertically depressible trap member mounted beneath the second named chute and yieldingly held in a horizontal position, and operative connections
20 from said trap member to said means for cutting off the power of the motor.
3. In an elevator structure, an elevator house, an endless elevator having buckets and having a vertical flight and a horizontal
25 flight disposed at the upper end of the

house, a housing inclosing a portion of the vertical flight and a portion of the horizontal flight of the elevator, the horizontal portion of the elevator terminating in a discharge chute, an auxiliary chute disposed 30 just beyond the discharge chute and into which said buckets discharge when the discharge chute is filled or clogged, a trap board yieldingly supported below said second named chute and yieldingly held in a 35 horizontal position, an electric motor for driving the endless elevator, a switch controlling the passage of current to the motor, a lever operatively engaging the switch and when shifted in one direction opening the 40 switch, and operative connections between the trap board and said lever whereby to actuate the lever upon the descent of the trap board.

In testimony whereof I hereunto affix my 45 signature in the presence of two witnesses.

ANDREW SORLIEN.
